UNITED STATES PATENT OFFICE.

JOHN HEBERLING AND WILLIAM L. HEBERLING, OF MOUNT PLEASANT,
OHIO.

TENSION-RELEASE.

SPECIFICATION forming part of Letters Patent No. 287,928, dated November 6, 1883.

Application filed July 19, 1883. (No model.)

To all whom it may concern:

Be it known that we, JOHN HEBERLING and WILLIAM L. HEBERLING, citizens of the United States, residing at Mount Pleasant, in the county of Jefferson and State of Ohio, have invented certain new and useful Improvements in Tension-Releases; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to improvements in devices for releasing the tension from the upper thread of sewing-machines; and it consists in the devices hereinafter fully described, and specifically pointed out in the claims.

In the drawings, Figure 1 is a perspective view, illustrating our invention applied to a sewing-machine head. Fig. 2 is a vertical detached section of the head and our tension mechanism. Fig. 3 is a sectional view similar to Fig. 2, except the tension in Fig. 2 is on the thread, while in Fig. 3 it is released. Fig. 4 is a detail view of the piston; and Figs. 5, 6, and 7 are detail views.

The object of our invention is to provide a convenient, simple, and easily-operated device for releasing the tension on the upper thread of the machine, so the work may be removed from under the needle readily, and without breaking the thread or injuring the needle.

Our tension-release is composed of the stud A, secured to the sewing-machine head, the coil-spring B, placed thereon, the disks C C, the piston D, and the thumb-nut E, all of which will be described.

In applying our invention to a machine we drill a mortise, f, in the front of the machine-head F, next the operator, and from the base of this mortise we form the threaded extension f', of smaller diameter than the said mortise.

The stud A is threaded at both ends and turned into this extension f', as shown. The outer end of this stud is formed with the longitudinal slot a, open at its outer end, as shown. This slot is made of a length to extend beyond

the position of the tension-disks when the latter are in place on the stud. The piston D is made of a size to slide in the slot a, and it is provided on one end with the ring d, fitted to move on the stud A, and on its opposite end is screwed or riveted the thumb-piece or button d'. This piston is placed ring end foremost in the stud A. The disks C C are then slipped over the piston and stud, followed by the thumb-nut E, which turns on the stud, and the button d' is screwed on the outer end of the piston, retaining the thumb-nut and disks from slipping off the piston, as well as providing a broad bearing for the thumb in operating the release.

The above, it will be seen, is the manner of applying the several parts when the ring d is secured permanently on the piston, and the thumb-piece d' is removable, as before described. It will be understood, however, that in the use of the preferred form of piston presently described, where the ring d is removable and the thumb-piece d' is permanently riveted in place, the operation as above is changed to the extent that the disks and nut E are placed on the piston before it is placed in the slot of the stud.

The spring B bears between the base of the mortise f and the ring d, and its outward pressure is thence applied to the disks, forcing them closely together. By means of the thumb-nut E the degree of tension may be readily regulated to suit the different-sized threads or the wishes of the operator.

When the several parts are in the position shown in Fig. 2, the tension is on the thread. In Fig. 3 the piston, by pressure on button d', has been forced in, the ring d pushing the spring B back, and the tension is released, and the thread may be readily drawn through the disks.

In constructing our piston, inner ring, &c., we prefer to stamp the whole out of sheet metal, in shape as shown in Figs. 6 and 7, so that the thumb-piece d' may be riveted permanently on the outer end of the piston D, while the ring d and the inner end of the piston D are so shaped that they may be attached or detached at will. This may be done by notching the edges of the

piston D near its inner end, as shown at $a' a'$ in Fig. 5, and forming the ring d with projections $e e$ on its inner side, to fit into the notches $a' a'$, so that if the inner end of the piston D be 5 inserted in the ring d while it is yet off the stud A and turned round in it the projections $e e$ on the inside of the ring will pass into the notches $a' a'$ in the piston, and if while 10 there the piston and ring are passed to their respective positions in and on the stud A they will be held intact by it, so as to retain 15 their proper relative positions with each other, as shown in Fig. 6.

It is apparent that when these parts are 15 made as just described the thumb-nut E and disks C C are all placed on the piston D from its inner end, while it is yet out of the slotted stud A, and before the ring d has been fixed upon it, and the disks, nut, &c., may be readily 20 separated from the piston, when the latter is removed from the stud, without the removal of the thumb-button, which, being permanently riveted to the piston, cannot become unscrewed and lost, as in case of the threaded button before 25 described, and shown in Fig. 4.

It will be seen that our device is simple, and is not liable to get out of order, and that it can be profitably applied to a great variety of sewing-machines, regardless of the internal mechanism of their heads.

Having thus described our invention, what we claim, and desire to secure by Letters Patent, is—

1. In a tension-release, the combination,

substantially as described and shown, of the 35 sewing-machine head having the mortise f formed in its front edge, and the threaded socket f' extended therefrom, the stud A, made smaller than mortise f, and having its inner end screwed into the extension f', and its outer 40 end provided with the slot a, the spring B, secured in the mortise f on the stud A, the piston D, placed in the slot a, and having the ring d secured on its inner end and bearing against the spring B, the tension-disks C C, 45 placed on the stud against the ring d, and the retaining and adjusting nut E, screwed on the outer end of the stud against the disks C C, all arranged and operating as and for the purposes specified.

2. The tension-release, substantially as described and shown, composed of the supporting-stud having a slot, a, formed in its outer end, the tension-spring, the disks, the retaining-nut, the piston fitted to the slot in the stud, and placed and movable therein, and having notches $a' a'$ formed in its inner end, and the ring d, having projections or lugs $e e$ extended inward therefrom into the notches $a' a'$ of the piston, all arranged and adapted to operate 55 substantially as set forth.

In testimony whereof we affix our signatures in presence of two witnesses.

JOHN HEBERLING.

WILLIAM L. HEBERLING.
